DESIGN FOR A STAPLING MACHINE

William G. Pankonin, Chicago, Ill.

Application March 26, 1941, Serial No. 99,908

Term of patent 14 years

To all whom it may concern:

Be it known that I, William G. Pankonin, a citizen of the United States, residing at Chicago, in the county of Cook and State of Illinois, have invented a new, original, and ornamental Design for a Stapling Machine, of which the following is a specification, reference being had to the accompanying drawing forming a part thereof, and in which:

Figure 1 is a view in front elevation of a stapling machine showing my new design;

Figure 2 is a top plan view thereof;

Figure 3 is a view in front end elevation; and Figure 4 is a view in rear end elevation.

I claim:

The ornamental design for a stapling machine, as shown.

WILLIAM G. PANKONIN.
